UNITED STATES PATENT OFFICE

2,477,276

SLIDABLY AND PIVOTALLY MOUNTED
MAILBOX

Hurshel K. Walton, Marshall, Mo.

Application March 18, 1947, Serial No. 735,321

2 Claims. (Cl. 232—39)

1

It is an important object of the invention to provide a mail box of the character described which is mounted on its support for vertical and horizontal movement to facilitate its use.

It is a further object of the invention to provide a mail box of the character described having a support member adjustable to a plurality of vertical heights relative to the ground.

Other objects and advantages of the invention will become apparent during the course of the following specification, and accompanying drawings, forming part of the specification, in which like numerals are used to designate like parts.

In the drawings:

Figure 1 is a side elevation of the mail box and its support, part of the support being shown in section.

Figure 2 is a front elevation of the mail box, and Figure 3 is a cross-section of the box, taken substantially on the line 3—3 of Figure 1.

Referring now in detail to the drawings, the numeral 5 designates a hollow rectangular-sectioned box bent outwardly approximately 45 degrees intermediate its ends to define a perpendicular bottom section 6 having a closed end 6' and an open-end upper section 7 having a hinged lid 8 provided with a spring snap 9 adapted to engage a member 10 on the front face of the said section 7. The front side of the said box is provided with a name plate holder 14, and a vertically disposed recessed member or guide means 15 is secured to the back of said section 6 closely adjacent and underlying the bend in the said box 5 for a purpose which will hereinafter become apparent.

A hollow member 16 provided with a finger grip 16' is pivotally mounted at 17 on the front side of section 7, adapted to receive and retain within the closed member until removed mail to be collected. An indicating flag 18 is pivotally mounted on the side of section 7 at 19, and a retainer clip 20 to secure the flag 18 when not in use is secured on the side of the said section.

A lever 21 is pivotally mounted at 21' on the side of section 7 closely adjacent the hollow member 16, the said lever being provided with three radially extending arms approximately 120 degrees apart, 22, 24 and 27. The arm 22 extends normally downward and is arranged with a balancing weight 23 at its free end. The arm 24 is provided with an extending flange 25 at its free end to support the flag 18 when raised from its engagement in the retainer 20, while the arm 27 is adapted to impinge against an extending pin 28 carried on the side of the member 16 to retain

2

the said member in closed and tight engagement with the front face of member 7.

A frame 29, adapted to carry an illuminated name plate is suspended from the bottom 6' by the rings 30.

The numeral 31 designates generally the support or supporting structure for my mail box. It comprises a vertical standard or tubular member 32 having a plurality of spaced-apart diametrically aligned holes 33 therethrough at one end thereof, the said member 32 being adapted to receive telescopically a cylinder member 34 having a plurality of diametrically aligned holes 35 therethrough, spaced apart to register with the holes 33 to permit passage of a bolt through the respective registering holes 33 and 35 to secure the member 32 on the member 34, a wing nut 37 being provided for retaining the bolt 36 in the registering holes. A wedge shaped anchor 38 having a dependent pointed element 39 is carried on the member 34, the anchor 38 and element 39 being adapted to be buried in the ground to support and anchor the structure 31 and the mail box 5.

25 A cap 40 is secured on the fore end of the member 32 by welding or otherwise and a horizontal arm or smaller diameter cylindrical rod 41 extends outwardly therefrom axially normal to the member 32, the said rod 41 being bent downward at a right angle a short distance outwardly of the cap 40 to provide a dependent portion 42, the end of which is pivotally mounted for rocking movement about a horizontal axis as by means embodying a pair of lugs 43 attached to a plate or connecting piece 44 arranged for up and down translative movement in the recessed member 15, tension between the said box 5 and the structure 31 being maintained for holding the box in fixed position on its pivot during such translative movement by a cable 45 which has one end secured between the lugs 43 and its other end secured to a ring 49 mounted on the rear of the section 7, the intermediate portion of the said cable passing successively through a ring 46 secured on the member 32 and a ring 48 depending from a collar 47 slidably mounted on the rod 41.

As may be readily seen, my box may be translated vertically in the recessed member 15 and pivoted both inwardly and outwardly relative to the structure 31 on the pivot member 50 for the convenience of the user. The supporting structure may also be adjusted vertically on the member 34 to suit the convenience of the owner.

I have described my invention in the form best known to me at this time. It is to be understood

however, that changes in the arrangement and form of the parts, or substitution of materials, may be made within the scope of the sub-joined claims without departing from the spirit of the invention.

Having thus described my invention, I claim:

1. The combination of a mail box, a vertically-positioned support, a horizontal arm having a depending end carried by said support, means pivotally mounting said mail box on the depending end of said arm for rocking movement about a horizontal axis, means carried by said mail box and operatively connected to said pivotal mounting means providing relative vertical movement of said box, and cable tension means connected between said box and said support and arm for maintaining said box in a fixed position on its pivot. 10
2. The combination of a mail box, a vertically-positioned support, embodying a vertical standard and a horizontal arm having a depending end carried by said standard, means pivotally mounting 15
- 20

said mail box on the depending end of said arm for rocking movement about a horizontal axis, guide means on the back of said box, a plate on the pivotal mounting means and slidably mounted within said guide means providing relative vertical movement of said box, and cable tension means connected between said box and said vertical standard and arm for maintaining said box in a fixed position on its pivot.

HURSHEL K. WALTON.
